UNITED STATES PATENT OFFICE

FRANCIS A. J. FITZGERALD, OF NIAGARA FALLS, NEW YORK, AND JAMES KELLEHER, OF CHIPPEWA, ONTARIO, CANADA, ASSIGNEES TO TITANIA CORPORATION, OF LOS ANGELES, CALIFORNIA, A CORPORATION OF CALIFORNIA

METALLURGICAL FURNACE

Application filed July 24, 1928. Serial No. 234,981.

It is well known to those skilled in the art that certain combinations of titanium oxide and carbon when subjected to heat in an atmosphere of nitrogen gas reacts to form carbon monoxide and titanium nitride, as clearly set forth in the United States Patents Nos. 1,391,147 and 1,391,148, issued September 20, 1921 to Bichowsky, et al.

The materials to be treated by our invention consist of titanium ore mixed with carbon and a suitable catalyst, such as sodium carbonate, as set forth in the Bichowsky patents. This material is ground to an extremely fine powder and mixed with some organic bond, such as glucose or molasses, after which it is briquetted so as to form a suitable charge for a furnace. One of the common methods of reducing such a charge is to place it in a shaft furnace, using coke as fuel, as for example the reduction of iron ores in a blast furnace. However, in the process for which our invention is designed, a fuel-fired furnace can not be used for heating the briquettes to the desired temperature, because the reaction will not take place except in an oxygen free atmosphere. Because of this reason it is essential that electric furnaces be employed, but an electric furnace with the usual shaft is not only difficult to control, but has a great many other objections, because of scaffolding, explosions, and the like.

The principal object of our invention has been to provide a furnace in which the process described in the Bichowsky et al. patent referred to may be practiced in a continuous manner for the production of titanium-nitrogen compounds.

Another object has been to provide a furnace in which the temperature of the reacting mass may be accurately controlled.

A further object has been to provide a furnace having heating means which shall uniformly heat the charge contained in the furnace.

Moreover, our furnace is provided with means for protecting the finished material from oxidation and for removing it from the furnace without permitting the escape of the nitrogen gas.

Furthermore, our furnace provides means

for preheating the nitrogen gas, and the untreated charge, and for recovering the combustible gases generated by the reaction.

The furnace hereinafter described attains the objects above recited and overcomes the disadvantages hereinbefore pointed out, and is shown in the accompanying drawings, of which:

Fig. 1 is a transverse, sectional elevation of our furnace, and is taken on line 1—1 of Fig. 2.

Fig. 2 is a longitudinal elevation of our invention and is taken on line 2—2 of Fig. 1.

Our invention consists of an outer casing 5, made of steel and having its joints welded so as to prevent the leakage of gas. The shell comprises a front wall 6, a rear wall 7, and end walls 8 and 9. A bottom 10 extends inwardly from the front wall 6 and a bottom 11 extends inwardly from the rear wall 7. The front wall 6 is provided with a lining 14, and the rear wall 7 is provided with a lining 15. The end walls 8 and 9 also have linings 16 and 17, respectively. These linings are made of refractory bricks of a type suitable to stand temperatures of between 1400° and 1500° C. The roof of the furnace comprises preferably a plate 20 which is made of graphite and may be supported by the linings 14, 16 and 17. This plate is preferably so arranged that it is removable. The top of the furnace and the roof 20 is covered with a layer 21 of suitable fire brick, carborundum fire sand, or the like.

Formed lengthwise in the top of the furnace, near the rear wall 7 thereof is a longitudinal charging hopper 22. A plate 23 serves to cover the hopper during the operation of the device. The lining 15 is wider near its bottom than it is near its top and an inclined surface joins the upper and lower portions of the lining, whereby a chute 18 is formed between the hopper 22 and the chamber 24 for conducting the briquettes into the furnace chamber 24. Arranged immediately above this chute, and preferably under the roof 20, is a gate 25 which may also be of graphite and which provides a fixed opening 26 at the end of the chute 18.

Arranged at the bottom of the chamber 24 and connecting the bottoms 10 and 11 is an in-

clined grate 30, comprising a stationary member 31 which may be welded to the bottoms 8 and 9 of the furnace shell. A movable member 32 is slidably carried by the stationary member 31 and is held in place preferably by means of the overhanging lips 33 of the stationary member. A shaker rod 34 is attached to the movable member and passes through the end furnace lining 17 and end wall 9 of the shell. A stuffing box 35 is carried by the shell at the point where the shaker rod passes therethrough so as to make a gas-tight joint. A shaker arm 36 is carried by the wall and provides means whereby the grate may be shaken. The grate members 31 and 32 are preferably made of plates which are provided with apertures 40 and 41, respectively. These apertures are brought into registration by the movement of the movable grate member 32. 15

20 Vertically extending rods 42 are carried by the movable member, and are moved through the charge in the furnace when the movable member is operated, whereby caking or crusting of the charge is prevented. The grate 30 is arranged at an angle which corresponds substantially to the angle of repose of the materials being treated, so that an even thickness of briquettes is maintained on the grate when the furnace is being operated, as indicated by 25

30 the dotted line 43 in Fig. 1. Obviously any suitable type of grate, other than that shown and above described may be employed in our device.

35 A discharge hopper 44 is located beneath the furnace and connects the bottoms 10 and 11. It is provided at its lower end with some suitable means of permitting the finished product to be discharged therefrom without permitting gas to escape during such discharge. For convenience, I have shown a rotatable valve 45 for accomplishing this end. This valve is provided with an opening 46 running preferably its full length and with end walls 47. The valve is cylindrical in form 40 and is mounted between suitable cylindrical surfaces 48 formed at the mouth of the hopper 44. A discharge opening 49 is formed between the tops of the surfaces 48 and a discharge opening 50 is formed between the bottoms of such surfaces. The proportion of the discharge openings 49 and 50, and the opening 46 of the valve are such, in relation to the length of the cylindrical surfaces 48, that upon rotation the discharge opening 49 will 45 be closed by the valve 45 before the opening 50 is opened by the registration therewith of the opening 46 of the valve. The end walls 47 of the valve are provided with shafts 51 which preferably pass through stuffing boxes 52 carried by the end walls 53 of the hopper, whereby leakage of gas is prevented at these points. Any suitable means such as a crank 56 may be attached to one of the shafts 51 for rotating the valve. 55

60 The furnace is preferably supported some

distance above the floor upon suitable legs or braces 54 and 55.

Arranged in the chamber 24, above the charge contained therein, is an electric resistor 60 which extends across the furnace and is held by two electrodes 61 and 62. These electrodes pass through the lining 14 and wall 6 of the furnace and are connected in any well known way with a suitable source of electric current. An observation tube 64 is 70 arranged in the top of the furnace and passes through the layer 21 of insulating material and roof 20, having its lower end extending into the chamber 24. This tube is made of any suitable material which will withstand 80 high temperatures and the action of carbon monoxide, such, for instance, as Acheson graphite. This tube is for the purpose of observing the rate of reaction and the progress of the reaction in the briquettes. 85 The observing tube is preferably provided with a cap 65 for closing its upper end during a part of the process.

A test tube 66 is provided which is carried by the layer 21 of insulating material and the roof 20. This tube is closed at its lower end and is of such a length that under normal conditions its lower end is embedded in the charge approximately one inch below the surface thereof. This tube may also be made of 95 graphite and is for the purpose of measuring the temperature of the briquettes under actual treatment by means of any suitable temperature indicating device, such as an optical pyrometer, thermocouple, or total radiation 100 pyrometer.

Since the Bichowsky processes are carried out in the presence of nitrogen I provide suitable means for supplying such gas to the interior of the furnace. These means comprise 105 tubes 70, 71 and 72. The tubes 70 and 71 are preferably arranged in the chamber 24 and immediately over the grate 30, so that the gas will pass up through the charge of briquettes disposed upon the grate. The 110 tube 72 is preferably arranged near the bottom of the discharge hopper 44. Each of these tubes may be formed with a slot 73 or suitable apertures may be provided if desired. The slots or apertures are arranged at 115 the lowermost point of the tubes so that they will not become clogged by the charge. By placing the tube 72 near the bottom of the hopper, the hopper is thus filled with nitrogen gas, thereby preventing any reversible 120 action that might occur when the titanium nitride is hot. The tubes may be formed of the ordinary iron or steel piping, and they may be suitably connected together, as shown in the drawings, and to a main supply pipe 125 74.

When carrying out the Bichowsky process by means of our device, the briquettes to be treated are fed into the charging hopper 22 until it is full. Because of the construction 130

and arrangement of the gate 25, the chamber 24 will also be filled to approximately the level shown by the dotted line 43. Nitrogen gas is now introduced into the furnace through the tubes 70, 71 and 72 until the air in the furnace is completely displaced by nitrogen. The charging hopper is now closed by means of the cover 23 and the observation tube 64 is also closed by means of the cap 65, whereby a slight internal pressure of the nitrogen gas is brought about and maintained within the furnace. The electric current is now switched on and, after a few minutes, the load in the furnace is brought up to its maximum so as to permit the most rapid heating of the furnace and briquettes. When the furnace temperature, as measured through the temperature tube 66 reaches approximately 1000° to 1100° C., the stream of nitrogen is increased, since a slight reaction takes place even at these temperatures. The rate of reaction is determined by opening the top of the observation tube 64 and observing the color of the flame and the chemical composition of the gases. It has been found that the optimum operating temperatures lie between 1100° and 1550° C., and when the furnace has attained the desired temperature for optimum rate of reaction, the required amount of nitrogen gas is permitted to enter through the tubes 70, 71 and 72. At this point the cover 23 of the charging hopper 22 is removed, permitting the gases to pass through the briquettes in this hopper. The gases passing out through the charging hopper and through the observation tube 64 consist primarily of carbon monoxide and nitrogen and react with any metallic oxides in the hopper 44, because the briquettes at this point will have reached a sufficient temperature to bring about a reducing action in an atmosphere of carbon monoxide, and in this place in the furnace it has been found that all the iron oxides present in the titanium ore are reduced and that, also, a preliminary nitrification of the material takes place. The gases passing up through the hopper 22 may be collected and used elsewhere, since they are combustible, or else they may be burned directly at the opening of the hopper. In the passage of these gases up through the hopper, the charge of briquettes contained therein are preheated before they are charged into the chamber 24 of the furnace.

When the briquettes on the top of the grate 30 have been treated for the required amount of time, the flame issued from the observation tube 64 will be seen to go down. The grate 30 is then shaken a definite amount, which will cause some of the treated briquettes to fall through the openings 40 and 41 in the grate members 31 and 32, respectively, and be deposited in the discharge hopper 44. After these treated briquettes are passed through the grate, a thin layer of green bri-

quettes coming from the charging hopper 22 and passing through the opening 26 is deposited upon the remainder of the treated briquettes resting upon the grate, where they will then be subjected to the treatment above described. A corresponding weight of briquettes in the green state is then fed into the charging hopper 22. The finished briquettes contained within the discharge hopper 44 may then be taken from this hopper by means of the cylindrical valve 45 which may be operated without the escape of gas from the hopper.

Since the discharge hopper 44 is not provided with any refractory lining, it will be seen that the heat contained in the finished briquettes as they are passed through the grate 30 will be permitted to radiate. If the radiation is not rapid enough to cool off the finished briquettes in the allotted time, water may be used in the hopper for the purpose. By cooling the briquettes before they are discharged through the valve 25, oxidation of the product is prevented.

The temperature of the briquettes, by means of our device may be maintained within very close limits by adjusting the amount of electrical energy supplied to the resister 60, which is an essential requirement in the carrying out of the Bichowsky processes.

The amount of nitrogen gas fed to the furnace is depended upon the rate at which the briquettes are being treated, and the point at which new briquettes are to be fed into the furnace, which is indicated by the flame condition at the opening of the observation tube 64. Since reaction does not take place until the nitrogen gas reaches the top of the charge, the gas will be preheated by the charge before it reaches the top thereof.

Obviously, some modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described our invention, what we claim is:

1. An electric furnace for the production of titanium-nitrogen compounds, comprising a refractory body forming a chamber, an inclined grate arranged at the bottom of the chamber for supporting the charge, and a radiant resistor carried by the body and arranged within the chamber some distance above the charge.

2. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the

charge, a charging hopper formed in the upper part of the body, and a chute connecting the charging hopper with the chamber.

3. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the charge, and means for admitting nitrogen gas into the chamber.

4. An electric furnace for the production of titanium-nitrogen compounds, comprising a refractory body forming a chamber, an inclined grate arranged at the bottom of the chamber, a radiant resistor carried by the body and arranged within the chamber some distance above the grate, a gas-tight discharge hopper arranged below the grate, and means for admitting nitrogen gas into the chamber and discharge hopper.

5. An electric furnace for the production of titanium-nitrogen compounds, comprising a refractory body forming a chamber, an inclined grate arranged at the bottom of the chamber, a radiant resistor carried by the body and arranged within the chamber some distance above the grate, a charging hopper formed in the upper part of the body, a chute connecting the discharge hopper with the chamber, a gas-tight discharge hopper arranged below the grate and means for admitting nitrogen gas into the discharge hopper.

35 6. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the charge, a charging hopper formed in the upper part of the body, a chute connecting the charging hopper with the chamber, and a gate carried by the body for limiting the size of the chute.

7. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the charge, a charging hopper formed in the upper part of the body, a chute connecting the charging hopper with the chamber, and means for admitting nitrogen gas into the chamber.

60 8. An electric furnace for the production of titanium-nitrogen compounds, comprising a refractory body forming a chamber, an inclined grate arranged at the bottom of the chamber for supporting the charge, a radiant resistor carried by the body and arranged

within the chamber some distance above the charge, and means for admitting nitrogen into the charge.

9. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the charge, and means for admitting nitrogen gas into the charge and immediately above the grate.

10. An electric furnace for the production of titanium-nitrogen compounds, comprising a refractory body forming a chamber, an inclined grate arranged at the bottom of the chamber for supporting the charge, a radiant resistor carried by the body and arranged within the chamber some distance above the charge, and means for directing a flow of nitrogen gas up through the charge.

In testimony whereof, we have hereunto signed our names.

FRANCIS A. J. FITZGERALD.

JAMES KELLEHER.
